UNITED STATES PATENT OFFICE

116,175

DESIGN FOR A SMOKING STAND

Chauncey E. Waltman, Chicago, Ill., assignor to
The Howell Company, St. Charles, Ill., a corporation of Illinois

Application June 21, 1939, Serial No. 85,599

Term of patent 3½ years

To all whom it may concern:

Be it known that I, Chauncey E. Waltman, a citizen of the United States, residing at Chicago, in the county of Cook and State of Illinois, have invented a new, original, and ornamental Design for a Smoking Stand, of which the following is a specification, reference being had to the accompanying drawing, forming a part thereof, in which the figure is a perspective view of a smoking stand showing my new design, the dominant features of my design residing in the parts shown in solid lines.

I claim:

The ornamental design for a smoking stand, as shown and described.

CHAUNCEY E. WALTMAN.
